Deuren s.c.

(57) **CLAIM**

We claim the ornamental design for laser target, as shown
and described.

DESCRIPTION

FIG. 1 is a front perspective view from above of an
embodiment of the claimed design;

FIG. 2 is a front perspective view from below of the claimed
design of FIG. 1;

FIG. 3 is a rear perspective view from below of the claimed
design of FIG. 1;

FIG. 4 is a front view of the claimed design of FIG. 1;

FIG. 5 is a rear view of the claimed design of FIG. 1;

FIG. 6 is a left side view of the claimed design of FIG. 1;

FIG. 7 is a right side view of the claimed design of FIG. 1;

FIG. 8 is a top view of the claimed design of FIG. 1;

FIG. 9 is a bottom view of the claimed design of FIG. 1;

FIG. 10 is a front perspective view from above of another
embodiment of the claimed design;

FIG. 11 is a front perspective view from below of the
claimed design of FIG. 10;

FIG. 12 is a rear perspective view from below of the claimed
design of FIG. 10;

FIG. 13 is a front view of the claimed design of FIG. 10;

FIG. 14 is a rear view of the claimed design of FIG. 10;

FIG. 15 is a left side view of the claimed design of FIG. 10;

FIG. 16 is a right side view of the claimed design of FIG. 10;

FIG. 17 is a top view of the claimed design of FIG. 10; and,

FIG. 18 is a bottom view of the claimed design of FIG. 10.

The ornamental design which is claimed is shown in solid
lines in the drawings. The broken lines in the drawings are
for illustrative purposes only and form no part of the claimed
design.

1 Claim, 14 Drawing Sheets
